207,186

COMBINED REFRACTOMETER AND ROTATABLE COVER THEREFOR

Donald E. Everburg, Southbridge, Mass., assignor to American Optical Company, Southbridge, Mass., a voluntary association of Massachusetts

Filed Feb. 24, 1966, Ser. No. 1,163

Term of patent 14 years

(Cl. D57—1)

FIG. 1 is a perspective view of a refractometer, showing the cover portion in its operating position, embodying my new design;

FIG. 2 is a bottom view thereof; and,

FIG. 3 is a top plan view thereof, showing the cover portion in its non-operating position.

I claim:

The ornamental design for a combined refractometer and rotatable cover therefor, as shown.
